(57) **CLAIM**

The ornamental design for a floor lamp as shown and described.

DESCRIPTION

FIG. 1 is a perspective view of a floor lamp showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the floor lamp where the lamp head is folded on the top of the lamp body;

FIG. 10 is a perspective view of the floor lamp where the first section of the lamp body and the second section of the lamp body are rotated by the same angle, the third section of the lamp body is rotated by a different angle;

FIG. 11 is a perspective view of the floor lamp where the second section of the lamp body and the third section of the lamp body are rotated by the same angle, the first section of the lamp body is rotated by a different angle;

FIG. 12 is an exploded perspective view of the floor lamp;

FIG. 13 is an enlarged view of portion 13 shown in FIG. 1;

FIG. 14 is an enlarged view of portion 14 shown in FIG. 1; and,

FIG. 15 is an enlarged view of portion 15 shown in FIG. 2. The dash-dash broken lines in the drawings depict portions of the floor lamp that form no part of the claimed design. The dot-dash broken lines represent boundaries of the enlarged portions and form no part of the claimed design.

1 Claim, 15 Drawing Sheets
